SACK SEWING APPARATUS

Vereau L. Stathem, Riverdale, Calif.

Application May 9, 1936, Serial No. 78,950

18 Claims. (Cl. 112—11)

This invention relates to a sack sewing apparatus intended to sew the mouth of a filled sack.

An object of the invention is to provide an apparatus of this kind comprising a sewing head together with a plurality of sack holders each mounted upon a carriage with all of the carriages positioned upon a turntable whereby while one sack is filling, a filled sack is properly presented to a sewing head for closing said filled sack.

Another object of the invention is to provide an apparatus of this kind comprising a filling station and a sewing station together with an intermediate turntable and a plurality of carriages mounted upon the turntable with a sack holding mechanism supported upon each of the carriages, said carriage being so arranged upon the turntable that a sack supported by one of the carriages is in a position to be filled while the second carriage is being caused to move with respect to the sewing station to sew the mouth of a filled sack.

An additional object of the invention is to provide an apparatus of this kind wherein is provided a sewing head together with means for moving a filled sack with respect to the head for closing the sack and means for automatically throwing off the filled sack after being sewed.

A still further object of the invention is to provide a filled sack sewing mechanism wherein is provided a carriage for carrying a filled sack and presenting the same to the stitching mechanism and wherein power means is provided to effect such travel of the carriage.

The invention also contemplates for an object to provide an apparatus of this kind which includes means for effectively cutting the thread after a filled sack has been sewed.

The invention consists in the details of construction and in the combination and arrangement of the several parts of my improved sack sewing apparatus whereby certain important advantages are attained and the device rendered simpler, less expensive and otherwise more convenient and advantageous for use, as will be hereininafter more fully set forth.

The novel features of my invention will hereinafter be definitely claimed.

In order that my invention may be the better understood, I will now proceed to describe the same with reference to the accompanying drawings, wherein:

Figure 1 is a view in side elevation and of somewhat a diagrammatic character illustrating a sack sewing apparatus constructed in accordance with an embodiment of my invention;

Figure 2 is a view in top plan of the structure illustrated in Figure 1;

Figure 3 is an enlarged detailed sectional view illustrating the means as herein employed for holding the turntable against movement;

Figure 4 is a longitudinal medial vertical sectional view taken through the structure.

Figure 5 is an enlarged transverse sectional view taken substantially on the line 5—5 of Figure 1;

Figure 6 is an enlarged fragmentary vertical sectional view taken longitudinally through the delivery end portion of the apparatus showing various positions of certain of the parts after the sack has been sewed;

Figure 7 is a detailed elevational view of the thread cutting knife as herein embodied;

Figure 8 is a detailed sectional view of the sack holding and throw off lever as herein comprised;

Figure 9 is an enlarged fragmentary vertical sectional view taken through the central portion of the platform with parts in elevation and illustrating in detail the mounting for the platform;

Figure 10 is a fragmentary horizontal sectional view taken substantially on the line 10—10 of Figure 9;

Figure 11 is a fragmentary detailed sectional view illustrating one of the supporting springs for the sack floor mounted on each of the carriages;

Figure 12 is a fragmentary top plan view of the sack holding means.

As disclosed in the accompanying drawings and particularly Figures 4 and 9, B denotes a base structure which may be constructed in any manner preferred and which has bolted, as at 1, or otherwise firmly mounted thereon a foot plate 2 which supports a stationary column 3. The lower portion of this column is larger in diameter than the upper portion to provide an annular shoulder 4 forming a support for an inner collar 5 constituting a wear and thrust bearing. Snugly surrounding this collar 5 is an outer collar 6 and interposed between the collars 5 and 6 are the anti-friction members 7.

The outer collar 6 is snugly received within the lower portion of a tubular shaft 8. This shaft 8 is of a length to terminate closely adjacent to the upper end of the stationary column 3. The upper portion of the shaft 8 has welded or otherwise rigidly secured therein an annular member 9 which provides a shoulder upon which rests the outer collar 10 of a second combined wear and thrust bearing. This collar 10 sub-

stantially snugly surrounds an inner collar 11 which rests upon an annular shoulder 12 carried by and surrounding the column 3 at a point closely adjacent its top. This shoulder 12 is preferably formed by again reducing the diameter of the shaft 3. The top of the shaft 3 has engaged thereon a nut or other holding member 14 co-acting with a washer 15. This washer 15 overlies the inner collar 11 to assure the same being maintained in applied position. Between the collars 10 and 11 are interposed the anti-friction members 16 herein disclosed as balls and which may, of course, be of a different character if required.

15 Resting on the upper end of the tubular shaft 8 is an end portion of an expansion spring 17, the opposite end of which bearing against a plate 18 intersecting the upper portion of an elongated sleeve 19. This sleeve 19 fits on and telescopes 20 upon the tubular shaft 8 but is free to have movement lengthwise thereof. The purpose of the spring 17 is to constantly urge the sleeve 19 upwardly, said sleeve being of a predetermined tension for a purpose to be later explained.

25 The shafts 3 and 8 are disposed centrally through a transverse channel beam 20 comprised in the structure of a platform P (see Figures 4 and 9). This platform P is positioned closely adjacent to the lower end of the tubular shaft 8 and is welded, as at 21, or otherwise rigidly secured thereto so that the platform P is effectively supported for turning or rotating movement with the shaft 8. The anti-friction mounting of the shaft 8 permits the platform to be 30 initially turned or rotated with a minimum of effort. While in the present embodiment of my invention the platform is intended to be manually turned or swung, it is to be understood that it is within the scope of my invention to provide 35 mechanical means for the same purpose. However, as any particular means for turning or swinging the platform does not constitute a particular part of the present invention an illustration and description of any such mechanical 40 means is believed to be unnecessary.

45 The transverse channel beam 20 is disposed between and suitably connected to the central portions of the longitudinally disposed side angle beams 22 comprised in the structure of the platform, said channel beam 20 constituting the sole support for the beams 22.

50 Welded or otherwise secured to the beams 22 at opposite sides but in close proximity to the transverse beam 20 are the upstanding angle irons 23. The upper ends of adjacent posts 23 are connected by the horizontally disposed angle bars 24. Welded or otherwise secured to the 55 posts 23 are the side plates 25 and suitably secured to the bars 24 is a top plate 26. These posts 23 and bars 24 together with the plates 25 and 26 provide a housing to prevent foreign matter, such as dust and the like, interfering with the lower mounting of the shaft 8. Each pair of corner posts 23 at a predetermined distance 60 below their upper ends have interposed therebetween and suitably connected thereto the angle bars 27. The two bars 27 support the parallel angle bars 28. These bars 28 adjacent each end portion are provided with a pair of transversely aligned bearings 29 for a shaft 30 and carrying a pulley 31.

65 Passing under the pulleys 31 is a flexible member or cable 32, the end plates 25 of the housing being provided with suitably positioned openings 70 33 for the passage of said cable outwardly from

75 said housing. The central portion of the top plate 26 is provided with a suitably positioned opening 34 through which the shafts 3 and 8 and the sleeve 19 freely pass, said opening 34 being also of a sufficient diameter to permit unobstructed passage therethrough of the vertical stretches of the cable 32. This cable 32 is disposed over and around a pulley 35 rotatably supported by the upper end portion of the sleeve 19 above the partition 18. Each extremity of the 10 cable 32 is suitably anchored, as at 36, to the inner end portion of a carriage 37 (see Fig. 4). The cable 32 is of a length dependent upon the extent of travel desired for each of the carriages 37 in a direction away from the shaft 3.

15 Each of the carriages 37 is provided with wheels 38 of a conventional type and mounting and which ride upon tracks 39 extending lengthwise along the beams 22 of the platform P at opposite sides of the central housing. These tracks 39 20 extend to the outer ends of the beams 22 and each of said tracks is adapted to be alternately brought into proper alignment with the tracks 39' suitably supported upon a stationary platform P' or other suitable support. This is shown 25 in Figures 4 and 6.

30 Each of the carriages 37 carries a yieldably supported floor 40 for coaction with a sack. Depending from the corner portions of the floor 40 are the bolts 41. These bolts 41 are fixedly secured to the floor 40 and are of substantial length. These shanks 41 are freely disposed through the floor 42 of the carriage 37 and mounted upon 35 said shanks 41 below the floor 42 are the nuts 43 for limiting the upward movement of the floor 40 with respect to the floor 42. Interposed between the floor 40 and the floor 42 are the coil springs encircling the shanks 41. These springs 44 are of a tension to normally hold the floor 42 at the limit of its raised position and 40 to materially resist the weight of a sack and its contents. The rear or inner bolts 41 have disposed therethrough at desired locations the stop pins 45 (see Figure 11) which will stop the downward movement of said rear shanks 41 so that 45 the forward or outer shanks 41 as they continue downwardly under the weight of the sack and its contents received upon the floor 40 will allow the floor 40 to have a downward tilting position as illustrated in Figure 6 to facilitate the throw off of the filled sack thereon.

50 The inner or rear end portion of the floor 40 is provided with an upstanding back wall 46 of a height to extend a considerable distance above of the filled sack on the floor 40. This wall 46 55 materially facilitates the desired throwing off of the sack.

55 The outer end portion of each of the carriages 37 at substantially its medial plane has pivotally engaged therewith an elongated depending pawl 60 47. This pawl 47 is normally urged and maintained in a raised position by a retractile member 48 herein disclosed as a coil spring, one end portion of which is suitably anchored, as at 49, to the pawl 47 and the opposite end portion secured, 65 as at 50, to a desired part of the carriage 37.

70 Partially underlying the stationary platform P' and also extending below the end portion of the platform P adjacent to the platform P' is an endless member 51, herein disclosed as a chain passing around the suitably positioned and supported sprocket wheels 52. The sprocket 52 in the present embodiment of my invention remote from the platform P constitutes the drive sprocket and its shaft 53 is adapted to be coupled with any suit- 75

able source of power, as for instance, a motor M. The endless chain 51 is disposed in a direction lengthwise of the rails 39' and positioned substantially midway thereof so that the outstanding lugs 54 carried at spaced points along the chain 51 may have proper contact with the pawl 47 to cause the carriage 37 to travel from its inner position upon the platform P outwardly upon the platform P' and for a distance sufficient to carry 10 the upper portion of the sack supported by the carriage through the head H of a sewing machine, indicated in Figure 1 and shown more in detail in Figure 5. Normally the pawl 47 is in its raised position and above the path of travel of the 15 upper standing lugs 54. However, when it is desired to have a carriage 37 move outwardly to effect the required sewing operation the operator pulls a lever 55 extending upwardly from a side beam 22 of the platform P. This lever 55 is loosely mounted on an end portion of a shaft 56 disposed transversely of the platform P and rotatably supported by the side beams 22 thereof. There is one of these shafts 56 carrying a lever at each end portion of the platform P and each lever 55 is adapted 20 to rock the shaft 56 remote therefrom and for which purpose the shaft 56 at a desired point thereon has pivotally engaged therewith, as at 57, an end of a connecting rod 58. The opposite end of this rod or link 58 is operatively connected, as at 59, with a crank arm 60 provided at an end portion of the shaft 56 remote from the lever 55. This crank arm 60 is at the end portion of the shaft 56 remote from the extremity upon which is mounted the second lever 55. It will, 25 therefore, be self-evident that the levers 55 are at opposite sides of the platform P but at the time of desired manipulation each of said levers 55 will be at the desired side of the platform for convenient working by the operator.

40 The normal raised position of each of the pawls 47 under the action of a spring 48 is limited by the pin A of a crank 61 formed in the middle portion of a shaft 56, and when lever 35 is in an approximately vertical position, the crank 61 will 45 extend upward and rearward.

45 Normally the carriages 37 are positioned entirely upon the platform P under the action of the spring 47 which constantly urges the sleeve 49 upwardly with the result that required pull is imposed upon the flexible member or cable 32 to 50 cause the carriages 37 to abut the end walls 25.

55 The inner end portion of each of the carriages 37 at substantially its transverse center is provided with a post 68 having braces 69. The upper end portion of the post 68 has firmly secured thereto an end portion of a beam 70 which extends outwardly with respect to the adjacent carriage in a direction lengthwise thereof. This beam 70 is of a length best required.

60 This beam 70 provides a support for a sack holding mechanism X which is of the detailed character disclosed in the patent granted to me on May 4, 1937, No. 2,079,132, said mechanism being of such character that it will support the 65 mouth of a sack open for filling and then tightly close the open end of the sack and holds it closed in such position that as the filled sack passes through the sewing head the mouth of the sack will be effectively stitched. This sack holder 70 holds the mouth of the bag open and, as illustrated in the accompanying drawings, a contact 71 is provided for engagement with a release lever 72 comprised in the sack holding mechanism whereby said mechanism is permitted to return to 75 its normally open adjustment and the filled sack

engaged therewith to drop therefrom upon the floor 40. This contact 71 as herein disclosed is operatively supported in required position from a vertical frame T positioned to one side of the inner or receiving end of the platform P'. The 5 sewing head H is secured to the upper portion of this frame T and the sewing mechanism comprised in the sewing head H is of a conventional type used in sack sewing and is driven from a shaft 73. As herein disclosed this shaft 73 is in 10 driven connection through the medium of a belt 74 with a pulley 75 freely mounted on a shaft 76 rotatably supported by the frame T.

This shaft 76 is in driven connection through the sprocket chain 77 with the drive shaft 53 15 hereinbefore referred to. This shaft 76 can, however, be driven otherwise if preferred.

Coacting with the pulley 75 and as shown in Figure 5 is a sliding clutch disk 78 mounted upon the shaft 76 for rotation therewith but movable 20 into or out of clutching engagement with the pulley 75. This clutch disk 78 may include, as is well known, a spring for normally maintaining de-clutching position but, as illustrated in Figure 5 of the accompanying drawings, the disk 78 is normally held in released position through the medium of a retractile spring 79 secured, as at 80, to the operating lever 81 for the clutch disk 78 and to a part 82 depending from the sewing head H. The lever 81 in the present embodiment of my invention is pivotally connected, as at 83, to a part 30 of the frame and at a desired point above the shaft 76, and the intermediate portion of this lever 81 is operatively engaged, as at 84, in a well known manner with the movable clutch member 35 78.

The lower end portion of the lever 81 has constantly in engagement therewith a roller 85 rotatably carried by the upstanding arm 86 of a bell crank lever. The heel portion of the bell crank 40 lever is pivotally mounted, as at 87, on the frame T with the second or lower arm 88 of the lever disposed in a general direction toward the platform P'. The arm 86 has engaged therewith a spring which serves to maintain the roller 85 in 45 desired constant contact with the lower portion of the lever 81 but not with sufficient pressure to cause any shifting of the lever. The tension of the spring 89 is considerably less than the tension of the spring 79.

50 While in the accompanying drawings I am showing the use of a spring 79 for normally maintaining the clutch member 78 in de-clutching position, I wish it to be understood that there can be used any type of clutch having in its own 55 structure a spring of desired strength and by referring to the spring 79 it is to be understood that I have in mind any other means which can be employed with advantage for maintaining this normal position of the clutch disk 78.

60 The arm 88 is of a length to lap or overlie either from above or below a side marginal portion of the floor 42 of each of the carriages 37 and the outer or free end portion of this arm 88 carries a roller 90 for such direct contact. The normal 65 position of the arm 88 is such to cause the roller 90 to engage the floor 42 of a carriage 37 from below but as a carriage 37 is moved from the tracks 39 outwardly of the platform P upon the tracks 39', a downwardly and outwardly inclined 70 cam surface or track 91 (shown in Figure 1) carried by the outer end of a carriage 37 at one side thereof will engage the roller 90 from below resulting in an upward swinging movement of the arm 88 and a simultaneous outward swinging 75 78

movement of the arm 86 against the lever 81. This action will cause the clutch member 78 to engage with the pulley 75 to make the sack sewing apparatus active whereby as the carriage 37 continues to travel outwardly the upper portion of the sack will be caused to travel through the head H and suitably stitched.

Just after the sack passes free of the needle or has been completely stitched, the roller 90 will 10 pass off the cam 91, the spring 79 will pull the lever 81 in a direction to declutch the member 78 and at the same time swing the arm 88 downwardly. This operation is permitted by recess 92 (see Figure 2) provided in the adjacent marginal portion of the floor 42 and suitably spaced inwardly of the cam track 91.

It is to be understood that the distance between the cam track 91 and the notch or recess 92 determines during what period of outward travel of 20 the carriage 37 the sewing mechanism of the head H will operate and for which reason it is important that such distance exceed the width of the filled sack.

After the filled sack has been sewed the stop 25 71 hereinbefore referred to, just before the working pawl 47 is released, will contact the lever 72 of the sack holding apparatus to allow the sewed sack to drop down upon the floor 40. The weight of the filled sack will tilt the floor 40 downwardly 30 and rearwardly and in most instances this action will cause the filled sack to be thrown off of the floor and which operation is further facilitated by the sudden tilting of the rear or back wall 46. However, should the sack not throw off quickly, 35 then as the carriage starts to return, the filled sack will come into contact with a throw off bar 94. This bar 94 is horizontally disposed and has its forward end portion pivotally connected, as at 95, to a suitably positioned support 96 preferably 40 arranged at the side of the platform P remote from the frame T. This bar 94 is constantly swung into a position to intersect the path of travel of the sack carried by the sack holding apparatus and is maintained in such position by 45 the expansible spring 97 interposed between the bar 94 and the support 96. The spring 97, as illustrated in Figure 8, encircles a bolt 98 pivotally connected, as at 99, to the bar 94 but having free sliding movement through the support 96. The 50 normal position of the bar 94 under the action of the spring 97 is determined by adjustment of the nut 100 threaded upon the outer end portion of the rod 98 for contact with the outer face of the support 96.

55 This bar 94 will readily swing inwardly as the carriage with the filled sack passes on the platform P' but will spring out to a position to engage the sack and stop the sack should the sack remain on the carriage 37 as said carriage travels 60 back upon the platform P. This contact of the bar 94 will assure the throwing off of the filled sack.

Just after the filled sack passes through the sewing head H it is, of course, important that the 65 sewing thread be severed. As herein disclosed, this is done by a blade 101 (Figures 6 and 7) having a cutting edge 102 in the form of an inverted V. The blade 101 is carried by an end portion of a vertically swinging arm 103 pivotally connected, 70 as at 104, to the supporting beam 70 closely adjacent its connection with the post 68. This arm 103 extends in a direction toward the outer or free end of the beam 70 so that as it is swung downwardly to sever a thread it will operate in 75 a direction opposite to the direction of travel of

the thread and thus eliminate undue waste of thread.

This arm 103 as herein disclosed has operatively engaged therewith a rigid link 105 which in turn is operatively engaged with an upstanding lever 106. This lever 106 is pivotally mounted upon the beam 70 and is positioned for contact by a trip member 107 extending laterally from an elongated bar 108 herein disclosed as extending from the casing of the head H. The stop 71 hereinbefore referred to depends from the rear end portion of this bar 108.

The carriages 37 at suitable points thereon have depending therefrom the rigid straps 109, each having at its lower portion a laterally disposed lug to engage below the side beams 22 of the platform P or the side beams 22' of the platform P'. These straps provide means to assure the carriages being maintained against displacement upon the rails 39 or 39'.

20 The general operation of this mechanism is as follows: The operator stands at the right in Figures 1 and 4. An empty sack is placed on the adjacent floor 40 with the mouth of the sack being held open by the sack holder mechanism designated generally X, which is fully shown and described in my copending application, Ser. No. 78,952, filed of even date herewith. The sack holder includes two axially rotatable jaws held from axial rotation by bolts, the bolts being released by a trip lever. When the bolts are released, the weight of the filled sack causes the jaws to turn downward, releasing the sack which permits all of the weight of the sack to be supported by the floor 40.

35 Assuming that a sack supported on the holder X, at the left hand side of the machine, as shown in Figure 1, has been filled, the operator releases latch 63 (see Figure 3) and rotates the platform P or turntable to carry the corresponding carriage with its filled sack into alignment with platform P', as shown in Figure 4. The operator then pulls the adjacent lever 55, which causes a depression of the pawl 47 of the carriage having the filled sack into the path of movement of one of the lugs 54. At this time, the carriage, which is now at the right hand in Figure 2, is bearing against the end wall 25 of housing 23. As the loaded carriage on platform P rolls toward and onto platform P', the spring 17 will be compressed to permit the cable 32 to pay out toward the left in Figure 4.

40 The upper end of the bag or sack with its mouth still engaged by the jaws of the bag holder X will pass into the sewing head H and as the forward upper corner of the sack enters the sewing head H, the cam 91 of the advancing carriage engages the roller 90, causing the clutch 78 to be thrown in, thus starting the sewing machine. When the bag has been fully sewed, the 45 thread is cut by the knife 101, the member 71, Figure 6, will trip the latch 72, which will release the axially rotative jaws of the holder X, releasing the sack and the whole weight of the sack will drop onto the bag supporting floor 40. This 50 will tilt the floor to the position shown in Figure 6 and usually throw off the sack. As soon as the lug 55 has passed out of engagement with pawl 47, the spring 17 will draw the emptied carriage back onto the platform P. If the bag should remain on the floor 40, the member 94 will dislodge it from its position and throw it off as the carriage moves from platform P' to platform P. Thus when the sack on platform P' has been 55 sewed and the sack on the right hand side of 75

platform P has been filled, the operator again throws lever 55 adjacent to his station, which lowers the pawl 47 of the carriage at the filling station. He then rotates the turntable to bring 5 the newly filled bag into position opposite the platform P' and the empty carriage to the filling station and repeats the operation.

It will be seen with this construction that the filling and the sewing of sacks is almost a continuous operation; that a filled sack does not have to be carried manually from one station to the other, and that each filled sack is properly positioned for sewing and is then discharged automatically.

15 From the foregoing description it is thought to be obvious that a sack sewing apparatus constructed in accordance with my invention is particularly well adapted for use by reason of the convenience and facility with which it may 20 be assembled and operated, and it will also be obvious that my invention is susceptible of some change and modification without departing from the principles and spirit thereof and for this reason I do not wish to be understood as limiting 25 myself to the precise arrangement and formation of the several parts herein shown in carrying out my invention in practice except as hereinafter claimed.

I claim:—

30 1. A filled sack sewing apparatus comprising a sewing means, a carriage movable rectilinearly in a path at one end adjacent to the sewing means, means for urging the carriage in a direction away from the sewing means, a sack supporting means mounted upon the carriage constructed and arranged to hold closed the mouth portion of a filled sack, said carriage as it moves in a direction toward the sewing means carrying the filled sack beyond the sewing means to 35 permit stitching of the closed mouth of the sack, and power means for moving the carriage toward the sewing means and manually operable means for connecting the carriage with the power operated means to shift the carriage into 40 active relation to the sewing means, and means acting automatically to release the connection between the power operated means and the carriage upon the completion of the sewing operation to thereby permit the return of the carriage under the action of the urging means.

50 2. A filled sack sewing apparatus comprising a sewing means, a carriage movable in a rectilinear path into coactive relation to the sewing means or away therefrom, means for normally urging the carriage to a position away from the sewing means, a sack supporting means mounted upon the carriage constructed and arranged to hold closed the mouth portion of a filled sack, means for moving the carriage into operative engagement with the sewing means and beyond the sewing means to permit stitching of the closed mouth of the sack, said last named means becoming ineffective when the carriage has travelled a distance sufficient to carry the filled sack beyond the sewing means, said urging means then acting to reverse the direction of movement of the carriage and return it to its initial position.

3. An apparatus of the class described comprising a rectilinearly movable carriage, an endless member separate from but having a flight travelling constantly in the same general direction as the direction of travel of the carriage, coacting means carried by the endless member and the carriage for moving the carriage a predetermined distance in one direction, means for

supporting a filled sack on the carriage, and means for stitching the mouth of the sack as the carriage is moved by the endless member.

4. An apparatus of the class described comprising a rectilinearly movable carriage, an endless member travelling in the same general direction as the direction of travel of the carriage, a movable pawl mounted on the carriage, a lug carried by the endless member to engage the pawl when in one position to cause the carriage to travel 10 in one direction, manually operable means to depress the pawl into the path of movement of the lug, means for supporting a filled sack on a carriage, and means for stitching the mouth of the sack as the carriage is moved by the endless member.

5. An apparatus of the class described comprising a carriage, an endless member travelling in the same general direction as the direction of travel of the carriage, a movable pawl carried by 20 the carriage, a lug carried by the endless member to engage the pawl when in one position to cause the carriage to travel in one direction, means for supporting a filled sack on a carriage, means for stitching the mouth of the sack as the carriage is 25 moved by the endless member, and means for normally holding the pawl in a second position free of the lug of the endless member.

6. An apparatus of the class described comprising a carriage, an endless member travelling 30 in the same general direction as the direction of travel of the carriage, a movable pawl carried by the carriage, a lug carried by the endless member to engage the pawl when in one position to cause the carriage to travel in one direction, means for 35 supporting a filled sack on a carriage, means for stitching the mouth of the sack as the carriage is moved by the endless member, means for normally holding the pawl in a second position free of the lug of the endless member, and means for 40 moving the pawl into its position to be engaged by the lug.

7. A sack sewing mechanism, including a turntable having a floor and having diametrically extending tracks on the floor on each side of 45 the rotative center of the table, a pair of sack supporting carriages, one on each track, means yieldingly urging both carriages toward the center of the turntable, a fixed platform having tracks with which the tracks of the turntable are 50 adapted to register, manually controllable power operated means operative to shift a carriage on the turntable onto the track of the fixed platform against the actuation of the urging means when the turntable track has been brought into 55 registry with a track on the fixed platform, sack sewing means carried on the fixed platform and engaging the mouth of the sack as the carriage moves onto the fixed platform, means automatically disengaging the carriage from the shifting means when the carriage is passed beyond the sewing means, and means for dislodging the sewed sack from the carriage upon a rearward movement of the carriage under the action of the urging means.

8. A sack sewing machine, including a fixed platform having a track, a turntable having diametrically extending tracks, one on each side of the rotative center of the table, a pair of sack supporting carriages associated one with each of 70 said tracks, means yieldingly urging said carriages toward the center of the turntable, means on each carriage for releasably engaging the mouth of a bag and holding said mouth closed, a power operated carriage moving element disposed in a line- 75

ment with the tracks of the fixed platform but extending below the path of movement of the turntable, the turntable when rotated carrying one of said carriages into position over said element, manually controllable means operable to engage a carriage when immediately above the element with the element to thus move the carriage onto the fixed platform for sewing, sewing mechanism on the fixed platform disposed adjacent to the path of travel of the carriage on the fixed platform and operating on the sack as the sack moves on the fixed platform, and means for automatically disconnecting the engagement between the carriage and the carriage moving element to permit the carriage to be returned to its initial position under the action of said urging means when the sewing has been completed.

9. A sack sewing machine, including a fixed platform having a track, a turntable having diametrically extending tracks, one on each side of the rotative center of the table, a pair of sack supporting carriages engaging said tracks, means yieldingly urging said carriages toward the center of the turntable, means on each carriage for releasably engaging the mouth of a bag and holding said mouth closed, a carriage moving element disposed in alinement with the tracks of the fixed platform but extending below the path of movement of the turntable, the turntable when rotated to one position carrying one of said carriages into position over said element, manually controllable means operable to engage a carriage immediately above the element with the element to thus move the carriage onto the fixed platform for sewing, sewing mechanism on the fixed platform disposed adjacent to the path of travel of the carriage on the fixed platform and operating on the sack as the sack moves on the fixed platform, means for automatically disconnecting the engagement between the carriage and the carriage moving element to permit the carriage to be returned to its initial position under the action of said urging means when the sewing has been completed, means for driving the sewing mechanism, and means for automatically connecting the sewing mechanism with said driving means as the sack enters the sewing mechanism and continuing said driving connection until the sack leaves the sewing mechanism and then automatically releasing said driving connection.

10. In the mechanism of the character described, a carriage having a floor adapted to support a filled sack, forward and rear springs on the carriage and upon which the floor is mounted, means for positively limiting the downward movement of the forward end of the floor, the rear end of the floor having full downward movement against the action of its springs, the floor having an upwardly extending wall at its forward end whereby when the weight of the sack comes upon the floor, the floor will tilt to discharge the sack.

11. In a sack sewing machine, a sewing head, a sack supporting carriage movable from a point remote from the sewing head past the sewing head to carry a sack thereon into operative relation to the head, power operated means directly engaging the carriage to shift the carriage toward and past the sewing head, means acting automatically to reverse the movement of the carriage after it has passed the sewing head, and means forcing the sack off the carriage upon such reverse movement, said means being disposed in the path of movement of the sack on the carriage and being yield-

able in one direction to permit the sack to be carried toward and past the sewing head.

12. A sack sewing mechanism, including a turntable having a floor, a pair of sack supporting carriages mounted upon the floor of the turntable for radial movement, a sewing head disposed beyond the turntable, the turntable being shiftable to position the carriages alternately in proximity to the sewing head, manually controllable motor operated means for shifting each carriage off the turntable into coactive relation to the sewing head to permit the bag on the carriage to be sewed, and automatically acting means for returning the carriage to its position on the turntable when the bag has been completely sewed.

13. Bag sewing mechanism, including a turntable having diametrically extending tracks on each side of the rotative center of the turntable, a pair of carriages mounted upon said tracks, a cable connecting said carriages, means at the center of the turntable engaging the middle of the cable and urging the middle of the cable upward whereby to yieldingly urge both carriages toward the middle of the turntable, a sewing head disposed beyond the turntable, the turntable being rotatable to carry the carriages alternately into proximity to the sewing head, manually controllable motor operated means adapted to operatively engage the carriage when the turntable is turned to bring a carriage into proximity to the sewing head and shift the carriage past the sewing head whereby a sack on the carriage may be sewed, said means automatically releasing the carriage after it has carried the sack through and beyond the sewing means to permit said cable to return the carriage to its initial position.

14. A sack sewing mechanism, including a turntable, a central vertically supported sleeve mounted on the turntable, a central vertical column extending into said sleeve, bearings for the turntable on the column, a pulley carried by the sleeve, a compression spring disposed between the upper end of the column and the upper end of the sleeve and thereby urging the sleeve and pulley upward, diametrically disposed tracks carried by the turntable, a pair of bag supporting carriages on said tracks, pulleys disposed adjacent the lower end of the sleeve and mounted on the turntable, a cable connecting said carriages, the cable passing beneath said pulleys and up over the pulley on the upper end of the sleeve, a sewing head disposed outward of the turntable, the turntable being rotatable to carry either of said carriages into position approximately opposite the sewing head, manually controllable means for shifting the adjacent carriage on the turntable outward past the sewing head to carry the bag thereon into operative engagement with the sewing head, the outward movement of the carriage being resisted by the compression spring, and means for automatically releasing the carriage from said shifting means when the bag has been completely sewed to thereby permit the spring and cable to return the carriage onto the turntable.

15. A rotatable platform, a sewing head supported adjacent to but exteriorly of the platform, carriages normally positioned on the platform but movable radially thereon, radial tracks on the platform providing a fixed path of travel for each of the carriages, means for holding the upper end of a filled sack and mounted upon

each carriage, said sack holding means being constructed and arranged to hold the mouth portion of a filled sack closed and to maintain said mouth portion of the sack in a position to be 5 stitched by the sewing head, and manually controllable means for moving each of the carriages off of the platform and past the sewing head when the platform has been moved to bring the carriage into proper position with respect to the sewing head.

16. An apparatus of the class described, comprising a rotatable platform, a sewing means positioned adjacent to but exteriorly of said platform, a plurality of carriages normally positioned on the platform but radially movable thereon, said platform being rotatable to selectively bring a carriage into working position with respect to the sewing means, means on each carriage for supporting a filled sack with its 10 mouth closed, means for moving the selected carriage off of the platform and into operative engagement with the sewing means, including an endless element having a flight constantly movable in one direction, the flight having means 15 for operatively engaging a carriage when the turntable has been turned to bring a selected carriage into a position adjacent the sewing means, said endless element acting to move the carriage beyond the sewing means to allow the sewing 20 means to sew the closed mouth of the sack, said endless element then releasing the carriage, and means acting automatically to return the carriage onto the turntable when so released.

17. In a machine of the character described, 25 a carriage having a floor adapted to support a filled sack, means above the floor and mounted on the carriage for engaging the upper end of a

sack and supporting the sack in erect position above the floor, forward and rear springs of equal strength upon which the floor is mounted, and means for positively limiting the downward movement of the floor at its forward end, the floor having full downward movement at its rear end whereby when the sack is released from the supporting means and drops upon the floor, the weight of the filled sack will cause the floor to tilt rearward to discharge the sack.

18. A sack sewing machine, including a turntable having a plurality of radial tracks, a fixed platform exterior to the turntable and having a track radial to the center of the turntable and having a bag sewing mechanism disposed above the track, the turntable being rotatable to bring any track into register with the track of the fixed platform, a carriage on each track and movable from the turntable onto the track of the platform when the corresponding track on the turntable 20 is in register with the track on the platform, a power operated endless element having a flight disposed below and parallel to the tracks on the platform and extending inward in a direction 25 radial to the center of the turntable, said flight of the endless element being driven in a direction toward the fixed platform, a member on each carriage shiftable into engagement with the endless element to thus cause the endless element to engage the carriage and shift it from the turntable onto the fixed platform and means on the turntable beneath each track 30 thereof engageable with the member on the corresponding carriage to shift it into position to be engaged by the endless element.
